UNITED STATES PATENT OFFICE

JOSEPH FOLK, OF LA PORTE, INDIANA, ASSIGNOR TO U. S. SLICING MACHINE COMPANY, OF LA PORTE, INDIANA, A CORPORATION OF INDIANA

POWER DRIVE MECHANISM FOR SLICING MACHINES

Application filed January 29, 1926. Serial No. 84,590.

This invention relates to slicing machines of the type having reciprocating feed tables and rotary slicing knives, and has for its object the provision of a motor drive for such machines which shall be of improved construction and operation.

The invention is exemplified in the combination and arrangement of parts shown in the accompanying drawings and described in the following specification, and it is more particularly pointed out in the appended claims.

In the drawings—

Fig. 1 is a fragmentary vertical sectional view through the knife spindle of a slicing machine showing one embodiment of the present invention;

Fig. 2 is a section substantially on line 2—2 of Fig. 1;

Fig. 3 is a section on line 3—3 of Fig. 1; and Figs. 4 and 5 are views similar to Figs. 1 and 2 showing a modification of the invention.

The numeral 10 in the drawings designates the frame of a slicing machine having a reciprocating feed table 11 and a rotary disc knife 12. The knife 12 is supported on the frame 10 by means of a pedestal or chain box 13 having a split collar 14 at its upper end. A housing member 15 is provided with a cylindrical projection or neck 16 which extends into the split collar 14 and is clamped in place therein by a cap screw 17. The housing 15 is provided with an opening 18 at the side thereof opposite the neck 16 and a cover plate 19 is removably secured in the opening 18. The knife spindle 20 is journaled in bearings 21 and 22 in the neck 16 and cover plate 19, respectively. The shaft 20 projects from the neck 16 at the side adjacent the reciprocating table 11 and carries a sprocket wheel 23 and the disc knife 12. A worm wheel 24 is loose on the shaft 20 within the housing 15 and is provided with a clutch face 25 which cooperates with a clutch 26 slidably mounted on the shaft 20 but held from rotation thereon by a pin 27. A spring 28 normally urges the clutch 26 into engagement with the clutch face 25. A plunger 29 extends through a central opening in the shaft 20 and bears against the pin 27. The outer end of the plunger en-

gages an adjustable set screw 30 having a lock nut 31 for holding it in place in a cap 32 rotatably mounted on a projecting stud 33 which is secured to the cover plate 19. The cap 32 is provided with inwardly projecting pins 34 which engage a cam groove 35 in the stud 33. A handle 36 is secured to the cap 32 for rotating the cap about the stud 33. Rotation of the cap moves the pins 34 in the cam groove 35 and thus forces the cap inwardly together with the plunger 29. This action will press the clutch member 26 to the right against the tension of the spring 28, as viewed in Fig. 1, and release the clutch 26. Opposite rotation of the handle will permit the spring to re-engage the clutch members. An index 37 may be provided for indicating the condition of the clutch for the various positions of the handle. The worm wheel 24 meshes with a worm 38 which is journaled in bearings 39 and 40 in the housing 15.

The housing 15 is provided with a downwardly extending flange 41 which supports a bracket 42 adjustably mounted thereon by cap screws 43. A motor 44 is carried by the bracket 42 and the shaft 45 of the motor is connected to the worm 38 by a suitable coupling 46. A switch 47 may be mounted on the housing 15 to control the motor 44. An opening 48 in the housing 15 is provided for inserting lubricating material into the housing. A suitable plug 49 is provided for closing the opening. The housing 15 is preferably made sufficiently tight so that it may be partially filled with lubricating material and a stop 50 is carried on the neck 16 and engages a pin 51 to hold the housing 15 at an angle so that the worm 38 is inclined to the horizontal. This raises the end of the worm 38 adjacent the motor 44 so that the tendency for the lubricating material to work out about the motor shaft 45 is reduced. The entire housing may, of course, be adjusted to various angular positions in the split collar 14, but the stop 50 and the pin 51 provide a limit for the downward movement of the motor. The entire motor housing may be readily removed by first removing the knife 12 and then sliding the neck 16 from the collar 14, the cap screw 17 being, of course, re-

leased. This arrangement makes it unnecessary to provide additional supporting brackets for the motor housing and makes it possible to replace the motor housing with the usual form of bearing bushing heretofore employed in hand operated machines. It will be seen that the sprocket wheel 23 corresponds to the usual knife spindle sprocket wheel of hand operated slicing machines as heretofore constructed and illustrated in van Berkell Patent No. 901,855 or Stukart Patent No. 1,144,507. The hand operated slicing machine of the type illustrated in these patents may be readily transformed into a power driven machine by removing the knife bushing from the hand machine and substituting the cylindrical neck 16 of the present invention which supports the gear housing and motor bracket. The sprocket chain 52 is connected through a sprocket wheel 53 and a shaft 54 to the main bevel gear 55 within the base 10 in the usual manner. The direction of drive is reversed, however, from that which is employed in a hand driven machine. Heretofore the drive shaft has operated from the bevel gear 55 through the sprocket wheel 53 and chain 52 to drive the knife spindle. By connecting the motor directly to the knife spindle the direction of the drive is reversed and advantage is taken of the speed reduction between the spindle and the operating mechanism for the reciprocating table by connecting the motor to the part having the highest speed of rotation. The table 11 is connected by a crank shaft 56 and a connecting rod 57 to the bevel gear 55 so that the motor drives the reciprocating table through the gear train described.

The coupling 46 is preferably in the form of a helical spring having one end secured to the worm shaft 38 and the other end secured to the motor shaft 45. This form of coupling has been found to be of great advantage because of the tolerance it permits in the alignment of the motor shaft and worm shafts.

In the form of the invention shown in Figs. 4 and 5, the motor is not supported in alignment with the worm shaft but instead the worm 38 is provided with an extension 60 journalled in a sleeve 61 supported in the housing 15. A motor housing 62 is suspended from the sleeve 61 and the motor 63 is mounted on the inner side wall 64 of this housing. The worm shaft is driven from the motor shaft by any suitable driving connection, such as a sprocket chain, belt, gearing or other driving connection. The arrangement brings the motor into closer relation with the other parts than does that shown in Figs. 1 and 2 and 3 and permits the use of a motor housing that presents the appearance of a unitary part of the slicing machine. One great advantage of this more compact arrangement is that the motor does not project rearwardly beyond the rear plane of the main portion of the slicing

machine. This is of great advantage where the rear portion of the machine is arranged against a wall or against the glass front of a show case.

I claim:

1. The combination with a slicing machine having a reciprocating table and a rotary knife spindle, of driving connection between said table and spindle, a bearing support, a bearing for said spindle carried by said support and angularly adjustable about the axis of said spindle, a gear housing carried by said bearing, a motor carried by said gear housing and adjustable therewith about the axis of said spindle, and gearing in said gear housing for connecting said motor with said spindle. 70

2. The combination with a slicing machine having a bearing support and a knife spindle, of a bearing removably mounted in said support and having said spindle journalled therein, a clutch mounted on said spindle, a housing for said clutch carried by said bearing, gearing for driving one member of said clutch disposed in said housing, a motor for driving said gearing, and a support for said motor mounted on said housing. 75

3. The combination with a slicing machine having a reciprocating table, a rotary knife spindle, and driving connection between said table and spindle, of a bearing support connected with said slicing machine and having a cylindrical socket therein, a gear housing having bearings for said spindle and having a cylindrical projection surrounding said spindle and fitting said socket, said cylindrical projection being mounted in said socket so as to be rotatable or longitudinally movable therein and means for securing said projection in said socket. 80

4. In a slicing machine, a support having a split sleeve, a housing having a collar removably supported in said sleeve, a knife spindle journalled in said housing, a worm shaft journalled in said housing and disposed transversely to said spindle, a clutch for connecting said worm shaft with said spindle, a motor suspended from said housing beneath the same, and means for driving said worm shaft from said motor. 85

5. A slicing machine comprising a knife spindle, a bearing support for said spindle, and a motor support carried by said bearing support and adjustable with said bearing support about the axis of said bearing support. 90

6. The combination with a slicing machine having a rotary knife spindle, of a bearing support, a bearing for said spindle carried by said support and angularly adjustable about the axis of said spindle, a gear housing carried by said bearing, and a motor support carried by said gear housing and adjustable therewith about the axis of said spindle. 95

7. A slicing machine having a knife spindle, a support for said knife spindle, a motor support carried by said spindle support, 100

driving means connecting said motor and spindle, said motor support being adjustable about the axis of said spindle while said driving means connects said motor and spindle.

5 8. A slicing machine comprising in combination, a material supporting table, a dished rotary slicing knife positioned adjacent said table, a motor for rotating said knife, a support for said motor and knife, a member carrying said motor and knife rotatably mounted in said support, said member being movable in the direction of the axis of said knife to adjust said knife with respect to said table.

10 9. In a slicing machine, the combination with a bearing member of a knife spindle journaled in said bearing member, a motor having a driving connection with said spindle and being offset relatively thereto, said motor 20 being adapted to be moved to various angular positions about said spindle for the purposes described.

15 10. A slicing machine comprising a bearing, a sleeve mounted for rotation in said bearing, a motor supported by said sleeve, a spindle rotatably mounted in said sleeve, a knife secured to said spindle, driving connections between said motor and said spindle, an abutment on said sleeve, a rigid abutment on 25 said bearing adapted to engage the abutment on said sleeve for limiting rotative movement of said sleeve in one direction, and releasable holding means for clamping said sleeve in any of its positions of adjustment.

30 11. A slicing machine comprising a bearing, a sleeve mounted for rotation in said bearing, a motor supported by said sleeve, a spindle rotatably mounted in said sleeve, a knife secured to said spindle, driving connections 35 between said motor and said spindle, an abutment on said sleeve, a rigid abutment on said bearing adapted to engage the abutment on said sleeve for limiting rotative movement of said sleeve in one direction, and releasable holding means for clamping said sleeve in any of its positions of adjustment, said motor being offset to one side of said spindle so that the weight thereof rotates said sleeve so that 40 the abutment on said sleeve is carried into engagement with the rigid abutment when said sleeve is permitted to rotate by releasing said 45 releasable holding means.

50 In testimony whereof I have signed my name to this specification on this 26th day of January, A. D. 1926.

JOSEPH FOLK.
